United States Patent Office

Des. 191,285
Patented Sept. 5, 1961

191,285

BOTTLE

Morton Edell, 37 Empire St., Newark, N.J.

Filed Mar. 24, 1961, Ser. No. 64,469

Term of patent 14 years

(Cl. D58—8)

FIG. 1 is a front elevational view of a bottle showing my new design, the back view being substantially the same; FIG. 2 is a top plan view thereof;

FIG. 3 is a side elevational view thereof, the side not shown being substantially the same; and

FIG. 4 is a bottom plan view thereof.

I claim:

The ornamental design for a bottle, substantially as shown and described.
